In Sweden October 31, 1949

9 Claims. (Cl. 169—4)

1

The present invention refers to the extinction of fire in tanks, containers or other storage rooms for combustible liquids, particularly tanks for inflammable oils, such as gasoline and crude oils.

The principle of fire extinction in tanks according to known methods aims at the provision of an insulating blanket of a fire extinguishing agent, generally foam, between the liquid and the air, thus starving the fire by stopping or retarding the evaporation. In a known method, the foam is supplied through the roof of the tank or through the upper portion of the wall of the tank by means of one or more inwardly projecting pipes, which are open toward the interior of the tank, and from these pipes the foam is introduced above the surface of the liquid in order then to flow out to cover the whole of the liquid surface, after sufficient quantities of foam have been applied, the result being then the "starving" of the fire. This method of supplying the foam is rather uneconomical, however, inasmuch as one must take into consideration that large portions of the foam will be broken down, when the foam passes directly through the flame-zone, which may have a temperature of up to 1000° C., or that the foam is carried off by the wind. For this reason another method (the subsurface method) has been evolved, according to which foam is pumped in through the ordinary supply lines for the oil directly into the oil, in which the foam has been permitted to rise to the surface. This method also suffers from a considerable drawback, inasmuch as the foam on its way in the oil up to the surface is broken down to a considerable extent, which is particularly the case with oils of a low viscosity, such as gasoline.

The primary object of the invention is to facilitate the supply of fire extinguishing agents to tanks or other storage rooms for combustible liquids in a manner more satisfactory than according to the known methods. The invention is based on the observation that, when a fire occurs in tanks containing an inflammable oil next to the liquid surface underneath the flame-zone, there is a layer consisting of evaporated oil, which maintains the fire when flowing in a constant current from the colder surface of the liquid. In this gas-zone the temperature is considerably lower than in the flame-zone thereabove. One object of the invention is to utilize this gas-zone for the supply of a fire extinguishing agent in a manner such that the supplying apparatus will not be made ineffective by the fire.

2

The invention comprises a method of fire extinction as well as a suitable contrivance for such extinction.

The method is primarily distinguished by the feature that a fire extinguishing agent, such as foam or an inert gas, is introduced into the storage room (the tank) at a point underneath the liquid surface therein through the combustible liquid, said agent being prevented on its way through the liquid from coming into contact with the latter, until it has reached the surface of the liquid or has been brought into the proximity of the same. The fire extinguishing agent may thus be introduced at a point of the wall of the tank located at a low level, if desired through the bottom of the tank, but for the conveyance up to the surface a contrivance is made use of, which prevents the fire extinguishing agent from coming into contact with the liquid and from being destroyed by the latter. For the conveyance one or more closed envelopes may be employed, into which the fire extinguishing agent is introduced, and the envelope is made from a material resistant to the contents of the tank, which material might be destroyed, however, through an influence from the heat of the fire on that portion of the envelope which, during the fire, is above the liquid surface in the tank, so that the envelope is opened by the fact that said portion is burnt off or fused, or is destroyed in some other way, so that the fire extinguishing agent is permitted to reach the surface of the liquid. The envelope may be constructed in various ways, and measures other than destroying a portion of the envelope may be resorted to for the opening of the same.

An apparatus devised in accordance with the invention is primarily distinguished by the feature that it is provided with a conveying means adapted to bring fire extinguishing means from a point on the wall of the storage room, which is located underneath the level of the liquid in this room, up to the surface of the liquid, in a manner such as to prevent the fire extinguishing means from coming into contact with the combustible liquid, until it has reached the level of the liquid, or has been brought to the proximity of the same.

The invention will be explained more closely in the following with reference to the accompanying drawings, which illustrate a few examples of embodiment. Fig. 1 is a vertical section of an oil tank under fire, this figure also showing zones caused by the fire. Figs. 2, 3, 4 and 5 are vertical sections, which each per se show an embodiment of a contrivance devised according to the inven-

tion and arranged on a tank. Fig. 6 shows a detail.

In Fig. 1, 10 designates a tank or other storage chamber or room for a combustible liquid, such as a gas oil. The upper surface of the liquid is located at 12. Under fire there is a zone 14 next to the surface of the liquid, said zone consisting of vapour, which in a constant current from the colder surface of the liquid maintains the fire. Here, the temperature is considerably lower than in the flame-zone 16 thereabove, the smoke zone 18 developing above said flame-zone. In the gas zone 14, where the temperature is comparatively low, as stated, a suitable fire extinguishing means, such as water or foam, is introduced according to the invention, said means being permitted to extend over the surface of the liquid so as to cut off the latter from the air evaporation and insulate the surface thus starving the fire (stopping the supply of gas).

If the level of the liquid in the tank were constant and known, the fire extinguishing means could be supplied from the side through a device located immediately above the surface of the liquid. In practice, the level of the liquid generally varies to a great extent according to the degree of filling of the tank. In order that the fire extinguishing means shall permit of being introduced at the proper level, without becoming destroyed by the heat from the flame-zone or by the liquid in the tank, it is introduced, according to the invention, at a point beneath the surface of the liquid, and is caused to pass through the liquid, it being prevented from coming into contact with the latter before having reached the surface of the liquid. The point of introduction is selected at a comparatively low level, preferably at the side of, the tank which also involves the advantage that the means of introduction become readily accessible.

To convey the extinguishing means from the point of introduction to the gas zone above the surface of the liquid, a conveying means may be employed, which within the scope of the invention may be formed in many different ways, a few of which are shown by way of example in the drawing. In principle, this contrivance is constituted by a shell or an envelope, into which the extinguishing means is introduced at the bottom to be conveyed to and delivered onto a point above or beside the surface of the liquid. Fig. 2 shows a tank 10, which is filled with a combustible liquid to the level 12, the envelope in consideration taking the form of a pipe or tube 20, which is permanently secured within the tank in a position suited for the supply of extinguishing means. A nozzle or socket 22 for the extinguishing means extends through the wall of the tank to adjoin the pipe 20. The pipe 20 extends in a vertical direction beside the wall of the tank, to which it may be secured. It is closed as the upper and the lower ends, but consists of a material, which is readily destroyed at a certain increase of the temperature, whereby the pipe is opened. At a fire, this destruction may thus consist in that the whole of the portion 23 of the pipe projecting above the surface 12 of the liquid is burnt off, so that extinguishing means supplied through the socket 22 can be pumped without impediment in a constant current up to the surface of the liquid to be spread over the latter. This device may be used for arbitrary extinguishing means, consequently not only for such having a specific gravity smaller than that of the liquid in the tank, such as foam and gas, but also for water

or some other extinguishing liquid. In the use of this device, it is possible, if desired, first to introduce water through the pipe to bring down the temperature on the surface of the liquid, whereupon foam or another extinguishing agent is applied.

In the construction according to Fig. 3, the tank 10, which is filled up to the level 12, is provided with an opening 24 at the bottom for the introduction of an envelope 26 intended to convey an extinguishing agent or means from a pipe conduit 28 up to the surface of the liquid. The envelope may take the form of a flexible hose or tube, which in a position of preparedness is lying folded in a pocket 30 between the pipe conduit and the opening 24. The outer end of the hose is secured with a tight fit to the inlet socket 25 of the pocket, so that leakage of liquid from the tank is prevented. Provided between the pocket and the opening is a cut-off valve 31 attached to a socket 32 surrounding the opening.

The valve 31 is normally closed, whereby liquid is prevented from escaping from the tank through the opening 24. At a fire, the valve 31 is opened, 25 the hose then preventing any discharge of liquid. Fire extinguishing agent is now supplied under pressure through the conduit 28 so as to fill the hose 26, which is pressed into the tank, where it unfolds. The hose is of a length such that it 30 may reach with its inner end for a distance above the surface of the liquid. In Fig. 3, the hose is marked in this position by dash lines 26. Various measures of expediency may be taken to bring the hose into this position. The simplest 35 way is to make use of a fire extinguishing agent, the specific weight of which is so much below that of the combustible liquid that the hose is caused to rise to the surface. Particularly suitable as a fire extinguishing agent is, therefore, a mechanically or chemically produced foam or some inert gas. Another way is to arrange a guiding means 40 within the tank, such as a rigid, preferably perforated pipe 33, through which the hose is directed upwardly during its projection. The hose must be closed against the contents of the tank while 45 floating up or rising to the surface, in order then to be opened, so that the extinguishing agent may find its way out to be spread over the surface of the liquid. An entirely automatic opening of 50 the hose may be achieved in a particularly simple manner by the hose being made from a material, which is destroyed, for instance by being ignited, and which then burns or melts under the influence of the heat of radiation from the flame- 55 zone. The hose may consist, for instance, of synthetic rubber, which loses its strength at a temperature as low as 70°, for example, and which is thus destroyed at the temperature prevailing in the gas zone (14 in Fig. 1). Plastic of a low 60 melting point is also serviceable. When the hose projects for some distance above the liquid surface 12, this projecting portion will therefore be opened, so that the extinguishing agent may find its way out.

65 The envelope need not take the form of a hose, but may have any suitable form, provided it is capable of conveying the extinguishing agent through the combustible liquid up to the surface of the latter, without the extinguishing agent and 70 the liquid being brought into mutual contact therewith. Another form is indicated by chain-dotted lines 40 in Fig. 3.

Irrespective of whether the envelope takes the form of a hose or not, it may be opened through 75 the influence of the pressure from the extinguish-

5

ing agent therein, the envelope then consisting of a more temperature-resistive, perhaps a refractory material, such as asbestos. To render this possible, the inner end of the envelope may be provided with breakage or weakening lines, for instance in the form of a circumferentially extending weakening line 34, as shown in Fig. 6, the end portion 36 thus bursting off, when the pressure has reached a sufficiently high value in the envelope. In place of such breakage lines, a valve may be provided, which is adapted to open through the pressure in the shell. This facility is elucidated in Fig. 5, which shows the hose 26 in a projected position with its upper end above the liquid surface 12. Arranged on the upper end is a valve member 36, which is kept in its closed position by a locking spring 38; the resiliency of this spring may be outweighed by the pressure in the hose, so that the valve can be opened through the influence of this pressure. If required, a float may be arranged in a suitable position on the hose, said float aiding toward bringing the end of the hose up to the surface of the liquid.

A special advantage of the closed pipe or hose employed according to the invention is that it forms itself a sealing means and in contradistinction to devices for introduction of foam through the tank roof improves the sealing possibilities and reduces the breathing losses.

As a conveying means for the extinguishing agent, particularly where the latter consists of foam or gas, balloons may be used in place of a pipe or a hose, said balloons being filled with an extinguishing agent and introduced into the tank in large quantities. An arrangement for this purpose is indicated diagrammatically in Fig. 4. A nozzle 46 is secured to the socket 34 in the wall opening 24 of the tank 10, and projecting into this nozzle is another nozzle 48. A pipe 50 opens into the space between the nozzles 46, 48. An agent, such as a suitable product of synthetic resin in a liquid state and capable of forming a film in contact with the contents of the tank is introduced through said pipe 50. This film-forming agent is pressed out into the annular opening 52 between the nozzles, and the film is dilated by the extinguishing agent introduced through the nozzle 48. In the example shown, the extinguishing agent is conceived of as consisting of foam created in a foam injector 54 provided with an injector nozzle 56, a water inlet 58, and an inlet 60 for a foam-forming agent. The film is closed by means of a device arranged in front of the nozzles 46, 48, so that the film is caused to form balloons 62, which in rapid succession rise to the liquid surface 12, where they are opened by the destruction of the film through the influence of the heat of the fire. For the production of the balloons any suitable apparatus may be used, which is capable of producing balloons in rapid succession, the ordinary means for the supply of gas as used in previously known balloon producing machines being used here for the supply of foam.

What I claim is:

1. An apparatus for extinguishing fire in tanks or other storage chambers containing an inflammable liquid comprising an inlet opening for introducing a fire extinguishing medium below the surface of said liquid, an envelope for said fire extinguishing medium adapted to be projected from said inlet opening to a point above the liquid surface, said envelope being made of material at least a portion of which is fusible but impervious

6

to said liquid, and means for projecting said envelope and said fire extinguishing medium from said inlet opening.

2. An apparatus for extinguishing fire in tanks or other storage chambers containing an inflammable liquid comprising an inlet opening for introducing a fire extinguishing medium below the surface of said liquid, an envelope for said fire extinguishing medium adapted to be projected from said inlet opening to a point above the liquid surface, said envelope being made of material at least a portion of which is fusible but impervious to said liquid, a pocket connected to said inlet opening for normally housing said envelope, and means for projecting said envelope and said fire extinguishing medium from said pocket.

3. An apparatus for extinguishing fire in tanks or other storage chambers containing an inflammable liquid comprising an inlet opening for introducing a fire extinguishing medium below the surface of said liquid, a collapsible envelope for said fire extinguishing medium adapted to be projected from said inlet opening to a point above the liquid surface, said collapsible envelope being made of material at least a portion of which is fusible but impervious to said liquid, a pocket connected to said inlet opening for housing said envelope in collapsed condition and means for projecting said fire extinguishing medium and said envelope from said pocket.

4. Apparatus for extinction of fire in tanks or other storage chambers for combustible liquids comprising a flexible tube being closed save for an inlet and made from a material resistant to the combustible liquid but destructible by the influence of the fire, said tube having an inlet below the liquid level in the chamber, means to keep said tube in a folded state of readiness, means to develop the tube through the liquid up to and above the surface thereof, where it is closed, and means to supply extinction means to said tube.

5. Apparatus for extinction of fire in tanks or other storage chambers for combustible liquids, comprising a flexible envelope being closed save for an inlet located below the liquid level in said chamber, means to supply extinction means to the envelope through said inlet, said extinction means having a specific gravity lower than that of the liquid in the chamber and thereby causing a portion of the envelope to rise to the surface of the liquid, the envelope being made of a material resistant to the liquid but destructible by the fire, whereby the envelope is automatically opened above the surface of the liquid due to the fire itself.

6. Apparatus for extinction of fire in tanks for combustible liquids comprising a pocket at the wall of the tank below the liquid level therein, said pocket having an inlet and an outlet, a flexible tube folded together in said pocket, said tube having an open end at the inlet and a closed end at the outlet, and means to supply extinction means into the tube to develop the tube in the liquid of the tank causing the closed end to rise above the liquid surface.

7. Apparatus for extinction of fire in tanks for combustible liquids comprising a pocket at the wall of the tank below the liquid level therein, said pocket having an inlet and an outlet, a flexible tube folded together in said pocket, said tube having an open end at the inlet and a closed end at the outlet, and a foam jet pipe for supplying foam under pressure into the tube to develop the tube into the liquid causing the closed end

of the tube to rise to the surface of the liquid due to the buoyancy of the foam.

8. Apparatus for extinction of fire in tanks for combustible liquids comprising a pocket at the wall of the tank below the liquid level therein, said pocket having an inlet and an outlet, a flexible tube folded together in said pocket, said tube having an open end at the inlet and a closed end at the outlet, means to supply extinction means into the tube to develop the tube in the liquid, and means guiding the tube for causing the closed end thereof to rise to the surface of the liquid.

9. Apparatus for extinction of fire in tanks or other storage chambers for combustible liquids, comprising an envelope having an inlet for extinction means but being closed save for this inlet, said inlet being located below the level of the liquid in the storage chamber, a pocket for said

envelope at the wall of the tank or chamber, said pocket being itself open toward the inner of the chamber but being closed by the envelope.
